UNITED STATES PATENT OFFICE.

FRANK HENRY DUTTON, OF JOHANNESBURG, TRANSVAAL, SOUTH AFRICA.

LIGHT-RAILWAY SYSTEM AND LOCOMOTIVE THEREFOR.

1,306,051.

Specification of Letters Patent. Patented June 10, 1919.

Application filed February 18, 1918. Serial No. 217,970.

To all whom it may concern:

Be it known that I, FRANK HENRY DUTTON, a British subject, and resident of Johannesburg, Transvaal Province of the Union of South Africa, (whose address is Room No. 182, South African Railway Buildings, Johannesburg, aforesaid,) have invented certain new and useful Improvements in Connection with Light-Railway Systems and Locomotives Thereof, of which the following is a specification.

The present invention relates to light railways of the type in which the load is carried on a rail track for ease of propulsion, while the driving wheels of the locomotive run on a parallel road track in order to give high tractive effort and to relieve the rail track of the driving load, so that it can be lightly and cheaply built.

Mono-rail systems of this type which have been proposed involve certain disadvantages limiting their practical application. The vehicles in such a system require to be provided with balancing wheels, usually on each side, which cause the vehicle, when in motion or on curves, or when unevenly loaded, to rock from side to side. The vehicles run partly on the mono-rail and partly on the ground alongside the track thus losing the great advantage of low tractive resistance gained by running on rails. If mono-rail vehicles are attached to a locomotive for balancing purposes all necessary freedom of action on curves is lost. Locomotives for mono-

rail systems that have been proposed are incapable of running backwards and have not the desirable flexibility to allow for the inaccuracies of alinement between the rail and the wheel way.

It is the object of the present invention to provide a simple and practicable system of the kind in question, and to provide certain novel constructions of locomotives therefor, as hereinafter described.

In the accompanying drawings

Figure 1 is a side elevation of one type of locomotive.

Figs. 2 and 3 are respectively a partial front and rear elevation.

Fig. 4 is a plan of the chassis.

Figs. 5 and 6 respectively an elevation and plan of another type of locomotive.

Fig. 7 is a plan of another locomotive.

Fig. 8 is a side elevation of the chassis thereof.

55

Fig. 9 is a detail sectional view taken on the plane A A Fig. 7.

Fig. 10 is a side elevation of a further type of locomotive.

Fig. 11 is a plan of portion of the chassis thereof.

According to this invention a two rail track 1, 1, Figs. 2, 3, and 4 is employed, on which run the wheels of the rolling stock and the guiding wheels of the locomotive.

65

At each side of the double rail track is formed a narrow wheel way 2, 2, of earth, road metal, concrete or the like on which run the rubber tired driving wheels of the locomotive.

70

The rolling stock 3 is of ordinary railway type having at least four wheels 4 all running on the rail track. It is thus self supporting and self balancing at all times; is not affected by inequalities between the rail track and the wheel way; is handled in the same way as rolling stock of ordinary light railways, and affords the minimum of tractive resistance.

75

The locomotive may be constructed to run only on the compound track or it may be adaptable for running both on said track and on an ordinary road. A locomotive of this latter kind can be detached and run around the train without requiring special loops for that purpose.

80

An example of this type is shown in Figs. 1 to 4. 5, 5, are the rear driving wheels, and 6, 6 the front steering wheels, all fitted with rubber tires 7.

90

When the tractor is used as a road vehicle all four wheels are on the road, the steering being effected by the usual steering wheels 8 operating on the front wheels 6. The rear wheels operate in the ordinary way as driving wheels rigidly alined with the back axle 9 in which is the differential gear 10.

95

The front wheels are controlled from the steering wheel 8 through the usual vertically pivoted stub axles 12, 12, which rotate in a horizontal plane within the axle brackets 11, 11.

100

The stub axles 12, 12, rotate horizontally on gun-metal nuts 70, 70 which are moved

up and down between the axle brackets 11, 11 by rotatable screws 13, 13. The screws are shown as driven by power from the engine 14 through a reversible friction clutch 15 and chain gearing 16.

17 is a four wheel bogie adapted for running on the rail track 1 and provided with the ball element 18 of a ball and socket joint. On the axle 19 or other convenient 10 part of the front of the tractor is provided the socket element 20 of the ball joint. To convert the tractor to a rail locomotive the tractor and the bogie are brought into the proper relative position, whereupon the 15 steering wheels 6, 6, are raised clear of the ground by means of the mechanism 15, 16, 13, 70 so bringing the ball joint elements 18, 20 together and causing the support to be transferred from the wheels 6, 6 to the 20 bogie 17.

During the forward traveling, the locomotive is guided simply by the bogie 17 traveling on the rails; the rear wheels, being trailing, follow the rail tracks, the ball 25 joint 18, 20 and the differential 10 in the back axle 9 permitting the paths of the rear wheels to conform closely to the rail track.

For reversed movement on the track, as 30 when shunting, the rear wheels 5, 5 are made steerable. For this purpose there is shown an auxiliary steering wheel 21 operating the stud axles 22, 22 on which are mounted the driving wheels 5, 5 through connections 23. The rear steering mechanism is ordinarily 35 kept locked by means represented by the vertically pivoted stops 24 which are brought into contact with stops 25 on the hubs of the driving wheels by means of a hand lever 26 operating through connections 27.

The trucks are connected for traction purposes to the locomotive by means of a draw bar 28 attached to the guiding bogie 17, thus obviating any undue vertical or horizontal 45 angularity either when curves are being traversed or owing to inequalities that exist between the levels of the rail track and wheelways. This arrangement also prevents any disturbing action on the driving wheels of 50 the locomotive by the trucks when descending steep grades.

The tractor is fitted with the usual change speed gears and reverse gear operated by lever 29.

55 Figs. 5 and 6 show a locomotive designed to remain on the track and arranged for forward and reverse movement at all speeds. It has a single pair of driving wheels 5, 5 on a differential axle 9 arranged about centrally of the length of the locomotive. Said 60 axle carries the necessary amount of the weight of the locomotive through the medium of springs 31.

Associated with the axle 9 is a four wheel

bogie 32 running on the rail track 1. Said 65 bogie is anchored to the engine frame by means of two ball joints 33, 33 and tie rods 34. The axle 9 is connected to the bogie by horns 35 which permit said parts relative vertical play either bodily or canting, but 70 keep them otherwise rigid, so that the bogie 32 keeps the wheels 5 running parallel with the rail track 1. The draw bars 36 are attached to the frame of the bogie.

Fore and aft of the bogie 32 are the two-wheel bogies 37, 37. Each of these is pivoted to the bogie 32 at 38, and is controlled by horizontal springs 39 which tend to keep the three bogies in line. The three bogies thus afford the stability against lateral oscillation due to the well known hunting action of bogies, while being free to pass easily around curves of short radius.

Each fore and aft bogie has at the top a roller path 40 on which bear rollers 41 carried on transverse leaf springs 42 thus supporting the locomotive against pitching and rolling. It will be apparent that the arrangement substantially obviates any deleterious effects due to inequalities of the 90 road track and the rail track and that in particular inequalities of the road track do not tend to throw the rail wheels off their track.

The motive arrangements comprise the engine 14, speed gear 29 and reversing gear 30.

A locomotive designed for greater tractive effort without however increasing the axle load on the rails is shown in Figs. 7, 8 and 9. It has two pairs of driving wheels 100 5, 5, 5, 5, carried on differential axles 9, 9. Said axles are connected to the locomotive frame by leaf springs 31.

44, 45 indicate two similar four-wheel bogies running on the rail track 1. 46 are 105 V frames depending from the main frame 47 of the tractor and carrying a longitudinal bar 48. Pivoted to each end of said bar 48 is a link 49 the other end of which is connected by a ball joint 50 to 110 one of the bogies 44, 45. Secured to the V frames 46 is spring 51 which transmits the desired proportion of the weight of the tractor to the bogies 44, 45.

The wheels 5 are carried on steering 115 driving axles 52 which are steered by the rail bogies 44 and 45, arrangements being made whereby the steering is effected by the leading bogie whether the movement is forward or reverse. All the steering axles 120 52 are connected by link work 53 to turn together. On each bogie 44, 45 is a disk 54, 55 formed with a slot 56 which engages a pin 57 on one of the connecting links 58. Said disks are rotatable and are connected by chain gearing 59 to rotate together. The slots 56 are at 90° with each other, and that on the leading bogie is

positioned longitudinally while that on the trailing bogie is transverse to the track. The former slot therefore engages its pin 57 operatively to actuate the steering link-
5 work 58 while the latter slot is inoperative.

It may be arranged that the necessary rotation of the disks 54, 55 to render them alternately operative and non-operative is effected by the reversing control 60 of the
10 locomotive.

The effect of the arrangement is that the leading bogie, upon turning when entering a curve, operates its rod 58 to turn the driving wheels into a following position.

15 This locomotive is, like the foregoing, provided with an engine 14, speed gear 29, and reversing gear 30 and with driving gear 61 to each axle 9.

20 Figs. 10 and 11 show a locomotive having two four wheel bogies, and driving wheels that are always trailing and therefore do not require steering.

The bogies 62 are connected by a link 63 and each carries a coupling 64 for a draw bar. Each also carries the ball element 65 of a ball joint.

25 Two pairs of driving wheels 5, 5, are provided, each pair near to one end of the tractor. Each pair is carried on a differential axle 9 mounted on a lever 66. Each of said levers 66 has at one end of the socket element 67 of a ball joint. At its other end it is connected to mechanical raising and lowering gear 68. Said gears 30 are both connected by means 69 to the engine 14 to be operated simultaneously; the arrangement being that one of the axles 9 is raised while the other is lowered. The socket end of the lever 66 of the lowered 35 axle engages the ball 65 on the adjacent bogie.

40 In practice, the leading pair of driving wheels 5, 5 are lifted clear of the ground. The weight of the tractor is therefore taken on the forward one of the bogies 62, and on the rear driving wheels which rest on the ground; the steering being effected by the forward bogie following the track. The rear bogie for the time being has no 45 function but to transmit the tractive effort from the forward bogie and the link 63 to the draw bar attached to its connection 64. When it is intended to reverse the locomotive the driving wheels which were 50 formerly raised are lowered and become operative; the bogie that was trailing becomes steering and vice versa.

I claim:

1. A light railway system, comprising a 55 two rail track, and two outside road wheel-ways, a locomotive having one or more four-wheel bogies pivoted to the frame and running on the rail track and one or more differentially driven pairs of driving wheels

shod with resilient tires running on the road 65 wheel-ways, and ordinary rolling stock running wholly on the rail track and attached for traction to the rail bogie of the locomotive.

2. A locomotive for a system of the kind 70 described, comprising a four-wheel bogie running on the rail track and pivotally attached to the locomotive frame, and one or more pairs of driving wheels carried on a differential axle, said driving wheels having 75 resilient tires and being arranged to run on the ground at each side of the rail track.

3. A locomotive for a system of the kind 80 described, comprising a four wheel bogie arranged to run on a rail track, a differential driving axle, driving wheels having resilient tires carried on said axle at a distance apart to straddle the track, said bogie being arranged for guiding the locomotive along the rail track and connections permitting 85 horizontal movement of the bogie relatively to the driving wheels.

4. A locomotive for a system of the kind 90 described comprising a four wheel bogie arranged to run on a rail track, a differential axle, driving wheels having resilient tires carried on said axle at a distance apart to straddle the track, said bogie being arranged for guiding the locomotive along the rail track and connections permitting both horizontal 95 and vertical movement of the bogie relatively to the driving wheels.

5. A locomotive for a system of the kind 100 described comprising a four wheel bogie arranged to run on a rail track, a differential driving axle, driving wheels having resilient tires carried on said axle at a distance apart to straddle the track, said bogie being arranged to control the direction of the driving wheels to guide the locomotive along 105 the rail track, and connections permitting horizontal movement of the bogie relatively to the driving wheels.

6. A locomotive for a system of the kind 110 described, comprising a four wheel bogie, at each end pivotally connected to the locomotive frame, differential axle means, and rubber tired driving wheels carried on said differential axle means and spaced apart to straddle the track.

7. A locomotive for a system of the kind 115 described, comprising two pairs of road wheels having resilient tires and a four wheel rail track bogie, said bogie and an adjacent pair of road wheels being arranged to 120 be alternatively brought into running position.

8. A convertible locomotive for a system 125 of the kind described, comprising front steering wheels and rear driving wheels for road locomotion, said rear driving wheels having resilient tires, a differential axle for the driving wheels, a four wheel bogie

adapted to run on a rail track, and pivotal means separably connecting the bogie to the front of the locomotive, said bogie when in place holding the front steering wheels clear of the ground.

9. A convertible locomotive for a system of the kind described, comprising front steering wheels and rear driving wheels for road locomotion, said driving wheels having

resilient tires, a differential axle for the 10 driving wheels, pivotal means at the front of the locomotive for disconnectably attaching a bogie, steering means for the rear driving wheels for rearward running and means for locking the rear wheels for forward 15 running.

In testimony whereof I affix my signature.

FRANK HENRY DUTTON.
